UNITED STATES PATENT OFFICE

ERNST LEYH, OF ESSEN, GERMANY, ASSIGNOR, BY MESNE ASSIGNMENTS, TO THE KOPPERS COMPANY, OF PITTSBURGH, PENNSYLVANIA, A CORPORATION OF DELAWARE

COKING RETORT OVEN

Application filed November 3, 1928, Serial No. 317,072, and in Germany November 28, 1927.

My invention refers to the production of gas and coke from coal and more especially to a coking retort oven of the cross regenerative type, in which the coking chambers containing the coal to be gasified alternate with heating walls traversed by vertical heating flues, while below the coking chambers and heating walls are arranged regenerators extending in the longitudinal direction of the coking chambers and heating walls and transversely to the longitudinal axis of the battery as a whole. An oven of this type which can be heated either with its own rich gas or with extraneously-derived special gas such as producer gas and the like was first described in U. S. patent to Koppers 818,033 dated April 17, 1906.

Ovens of this cross-regenerative type involve the disadvantage, more especially when they shall be heated with preheated air and preheated poor gas, that the brick work partitions separating the regenerators and which are inserted between pairs of regenerators traversed in opposite directions, measure about 300-450 square feet and, on the operation of the oven being started and the whole block of chambers undergoing considerable expansion, have a great tendency to crack. This formation of cracks or fissures in the brick work inevitably results in losses of gas and air passing through the brick work from the upflow to the downflow regenerators.

In order to obviate these drawbacks, Friedrich Totzek in a copending application for patent of the United States entitled "Retort oven for producing gas and coke" has suggested arranging the regenerators for communication with the heating walls in a peculiar manner. Pairs of regenerator chambers extend in line underneath the heating walls and coking chambers from the pusher side to the coke side. Each of the two chambers of each pair communicate directly with the corresponding halves of the heating walls above it by means of short ducts extending from the top of the chamber, while the heating flues in the other halves of these heating walls, being arranged above the other regenerator chamber, communicate with the first chamber through a canal extending from

the inner top corner of this chamber and between the other chamber and the heating flues above same, separate ducts leading from the canal to these flues. In this manner both chambers of each pair of regenerator chambers in the cross regenerative coke oven, although extending only halfway across the oven, are connected with all the flues of the heating walls above the regenerator, whereby the flow of gases in each heating wall is rendered uniform all over its length and each gas particle, no matter which way it may travel within the battery, always encounters the same total resistance, the distance through which it passes, being always equally long.

While in Friedrich Totzek's application for patent mentioned above his invention was shown and described in application to an oven of the hair-pin flue type, in which the flues in each heating wall are combined in pairs operating alternately as upflow and downflow flues.

I have found that by applying the new principle of construction and gas and air distribution to that type of coke ovens which is described for instance in Becker's U. S. Patent 1,374,546, such ovens will also be greatly improved. In this type of ovens adjoining heating walls are combined in pairs for cooperation, a passage extending from one heating wall of a pair and above the coking chamber arranged between them to the heating wall on the other side of the coking chamber and the burning gas mixture ascending in one of the two heating walls will pass above the coking chamber and descend in the other heating wall.

In the drawings affixed to this specification and forming part thereof an oven embodying my invention is illustrated diagrammatically by way of example.

In the drawings

Fig. 1 is a cross section of the battery of coke ovens, being a longitudinal section of a heating wall and regenerator on the line B—B in Fig. 2.

Fig. 2 is a partial longitudinal section of the battery of ovens on the line A—A in

Fig. 1.

Fig. 3 is a horizontal section on the line D—D and

Fig. 4 is a similar section on the line E—E in Fig. 1.

5 Referring to the drawings, 9 are the coking chambers and 10 and 11 are pairs of rows of combustion flues forming heating walls enclosing the coking chambers between them. Above the flues in each heating wall extends 10 a horizontal bus flue 4. The bus flues of two adjoining heating walls are connected by a number of U-shaped cross-over passages 12.

Underneath the coking chambers and in parallel therewith extend the pairs of regenerator chambers filled with checkerwork, the chambers of each pair being separated by a partition 13, the combined partitions forming a wall extending throughout the length and in the middle axis of the battery of coke ovens 20 (Fig. 4). The chambers of adjoining regenerators on the coke side are marked 14 and 15, those on the pusher side 14a and 15a, respectively. Each chamber communicates with all the heating flues of a heating wall, 25 communication with those flues which are arranged directly above it, being established by short ducts extending from the regenerator directly to the bottom of the flues, while a canal extending from the inner top corner 30 of the chamber first in slightly ascending direction and thereafter horizontally above the other chamber and below the heating flues arranged above this latter communicates with these flues by means of short ducts of its 35 own. In the case illustrated in the drawings the right hand regenerator chamber 14 shown in Fig. 1 directly communicates with the heating flues 11 directly above it by ducts 17, while communication with the heating 40 flues in the left hand half of the same heating wall is established by the canal 18a and ducts 17a. In a similar manner the left hand chamber 14a of the regenerator is in direct communication with the left hand half of 45 the adjoining heating wall 10 by means of flues 16a, while communication with the right hand half of the flues in this heating wall is established by the canal 18 and ducts 16. Similar canals 19, 19a are provided for communication between the regenerator chambers 15 and 15a and the heating walls 11 and 50 10, respectively.

Assuming the regenerator chambers on the right hand side to be in course of preheating 55 and the oven to be heated with extraneously-derived gas, gas will for instance enter the regenerator chambers 14 through sole channels 24 (Fig. 1), air entering the regenerator chambers 15 through similar sole channels 60 (not shown). The gas and air in passing through the chambers are preheated in contact with the hot checkerwork and enter the right hand half of the heating flues directly through ducts 17 and 16, respectively, while 65 the heating flues in the left hand half of the

same heating walls are supplied with pre-heated air and gas through the canals 18a and 19a and ducts 17a and 16a, respectively. After combustion the hot waste gases will pass from the heating wall through the bus flue 4, 70 above the heating wall, through the passages 12 into the bus flue above the other heating wall of the pair and down through the flues in this wall, escaping through ducts 16a and 17a, canals 18 and 19 and regenerators 14a 75 and 15a, respectively.

Obviously after reversal, the direction of flow of the air and gases is reversed also.

At 30 in Fig. 2 is shown the rich gas pipe from which rich gas is conducted in a well known manner into the heating flues from below. Obviously it is also possible to supply rich gas from chambers provided below the oven structure by means of pipes extending through the supporting walls, and it is further possible to supply gas in steps or at the lower end of the upflow or the upper end of the down-flow rows of heating flues.

I wish it to be understood that I do not desire to be limited to the exact details of construction shown and described for obvious modifications will occur to a person skilled in the art.

I claim:—

1. Coking retort oven comprising a horizontally elongated coking chamber, a pair of heating walls alongside and one on each side of and parallel to said coking chamber, vertical combustion flues in each of said heating walls, and a horizontal bus flue in each of said heating walls communicating with the vertical flues in the same wall, a passage extending above said coking chamber and communicably connecting the bus flues on opposite sides of said coking chamber, a pair of regenerator chambers extending in line below and parallel with said coking chamber and heating walls, each of the regenerator chambers extending from one end to the middle of the oven, ducts establishing direct communication between one of said regenerator chambers and the vertical flues of one half of one of the heating walls, a canal extending between the other regenerator chamber and the other half of the same heating wall and communicating with said one of said regenerator chambers at the inner part thereof and communicating by ducts with the vertical flues of said other half of the same heating wall, ducts establishing communication between said other regenerator chamber and the vertical flues of one half of the other heating wall, a canal extending between said one of said regenerator chambers and the other half of said other heating wall and communicating with said other regenerator chamber at the inner part thereof and communicating by ducts with the vertical flues of said other half of said other heating wall.

2. Coking retort oven comprising a hori-

zontally elongated coking chamber, a pair of heating walls alongside and one on each side of and parallel to said coking chamber, vertical combustion flues in each of said heating walls, and a horizontal bus flue in each of said heating walls communicating with the vertical flues in the same wall, a passage extending above said coking chamber and communicably connecting the bus flues on opposite sides of said coking chamber, a pair of regenerator chambers extending in line below and parallel with said coking chamber and heating walls, one of said regenerator chambers and the vertical flues of one half of one of the heating walls, a canal extending between the other regenerator chamber and the other half of the same heating wall and communicating with said one of said regenerator chambers at the inner part thereof and communicating by ducts with the vertical flues of said other half of the same heating wall, ducts establishing communication between said other regenerator chamber and the vertical flues of one half of the other heating wall, a canal extending between said one of said regenerator chambers and the other half of said other heating wall and communicating with said other regenerator chamber at the inner part thereof and communicating by ducts with the vertical flues of said other half of said other heating wall, the inner ends of the said canals being inclined to the horizontal, the remaining portions of the canals being parallel to said heating walls and the inner ends of the canals crossing each other in spaced relation.

In testimony whereof I affix my signature.
ERNST LEYH.

zontally elongated coking chamber, a pair of heating walls alongside and one on each side of and parallel to said coking chamber, vertical combustion flues in each of said heating walls, and a horizontal bus flue in each of said heating walls communicating with the vertical flues in the same wall, a passage extending above said coking chamber and communicably connecting the bus flues on opposite sides of said coking chamber, a pair of regenerator chambers extending in line below and parallel with said coking chamber and heating walls, one of said regenerator chambers and the vertical flues of one half of one of the heating walls, a canal extending between the other regenerator chamber and the other half of the same heating wall and communicating with said one of said regenerator chambers at the inner part thereof and communicating by ducts with the vertical flues of said other half of the same heating wall, ducts establishing communication between said other regenerator chamber and the vertical flues of one half of the other heating wall, a canal extending between said one of said regenerator chambers and the other half of said other heating wall and communicating with said other regenerator chamber at the inner part thereof and communicating by ducts with the vertical flues of said other half of said other heating wall, the inner ends of the said canals being inclined to the horizontal, the remaining portions of the canals being parallel to said heating walls and the inner ends of the canals crossing each other in spaced relation.

In testimony whereof I affix my signature.
ERNST LEYH.
